UNITED STATES PATENT OFFICE

WOLFGANG HERMANN, OF CHICAGO, ILLINOIS, ASSIGNOR TO METAL SPECIALTIES MANUFACTURING COMPANY, OF CHICAGO, ILLINOIS, A CORPORATION OF ILLINOIS

ELECTRIC-REEL SWITCH

Application filed January 20, 1926. Serial No. 82,522.

This invention relates particularly to electric reels adapted for use in connection with electric cigar-lighters, electric lamps, etc.

The improved device is particularly useful in connection with automobiles, and especially in connection with cigar-lighters for automobiles.

The primary object is to provide improved means for controlling the electric circuit. In accordance with this invention, the electric circuit of the cigar-lighter, for example, is automatically broken during the initial portion of the rewinding operation, and is automatically made during the initial portion of the operation of unwinding the electric cord from the reel.

In accordance with the preferred embodiment of the invention, the reel is provided at one end with a contact member, and the frame or casing is provided with a co-acting contact member; and an independently movable circuit-controlling device in the form of an insulation strip is interposed between the planes of the contact members and has a limited travel with the reel in one direction to make the circuit during the initial portion of the unwinding of the cord, and has a limited travel with the reel in the opposite direction to break the circuit during the initial portion of the rewinding of the cord.

The rewinding of the reel is effected by means of a clock spring in a well known manner.

Preferably, the insulation strip mentioned, which operates as a circuit-maker-and-breaker, is frictionally moved by the reel during the initial portion of the unwinding operation and allows the leaf-spring contact member mounted on the frame, or casing, to come into contact with the annular contact member of the reel, the movement of the insulation strip being limited by a stop with which the casing is provided, while the reel is free to continue its movement of rotation; and in the reverse movement (the rewinding), the insulation strip is returned by the frictional action of the reel during its initial rewinding movement to its original circuit-breaking position, where it remains in readiness to maintain an open circuit after the electric cord has been fully rewound upon the reel.

The invention is illustrated in its preferred embodiment in the accompanying drawings, in which—

Fig. 1 represents an elevational view of a cigar-lighter embodying the invention; Fig. 2, a broken elevational view of the reverse side of the cigar-lighter; Fig. 3, a view similar to Fig. 1, but showing one side of the frame, or casing, removed; Fig. 4, an inner view of the removed side of the casing, showing it equipped with a spring-contact member; Fig. 5, a view showing the casing and the reel removed therefrom and reversed; Fig. 6, an elevational view of the reel and attendant parts; Fig. 7, a view of the handle employed for turning the shaft to apply tension to the spring employed; Fig. 8, an enlarged sectional view taken as indicated at line 8 of Fig. 1; Fig. 9, an edge elevational view, partly in section, of the removable side-wall of the casing, showing the leaf-spring contact member carried thereby; Fig. 10, a broken inner perspective view of the removable side-wall of the casing; Fig. 11, a broken perspective view of the peripheral wall of the casing; and Fig. 12, a perspective view of a tension member employed which is interposed between one wall of the casing and the frictionally actuated contact-maker-and-breaker.

In the embodiment of the invention illustrated, A designates a frame, or casing, which comprises a main casing section A' and a removable cap A², the main casing section being equipped with a clamping tube A³ adapted to be clamped to a dash of an automobile, for example; B, a reel mounted so as to be capable of revolving on a shaft B' whose ends are supported in the side-walls of the casing, one end of said shaft being equipped with a removable handle B² which is adapted to engage any one of a series of ratchet-lugs B³ with which the casing is equipped; C, a main spring confined in a chamber formed in one side of the reel and having one end attached at 1 to the shaft, and the other end attached at 2 to the reel; D, a cigar-lighter tip carried by a tubular handle D' which is adapted to be sheathed within the tube A³; and E, an electric cord which is in electrical connection with the cigar-lighter.

tip, said cord being adapted to be wound upon the reel B.

The casing A may be of any suitable construction. Preferably, it is made from sheet metal and has the clamping-tube A³ secured 5 to it in tangential relation. Ordinarily, the clamping-tube is threaded and equipped with nuts 3. Thus, the tube may extend through a perforation in the dash and may be clamped to the dash in a well known manner, thus 10 supporting the casing.

The removable cap A² of the casing is provided with a central perforation 4 adapted to receive one end of the shaft B'. The opposite 15 end of said shaft is provided with suitable grooves 5 for receiving the forked end of the handle, or lever, B², as will be understood from Figs. 2, 6 and 7.

In the preferred construction being described, the reel B is formed mainly from 20 sheet-metal and is in electrical contact with the shaft B', and through said shaft with the casing. The main section of the reel is equipped with a flange 6. The opposite flange 25 7 of the reel affords an annular contact member which is insulated with respect to the main section of the reel. The annular contact member 7 is carried by insulation disks 8 which are secured to one end of the barrel of the 30 reel.

The annular contact member 7 of the reel coacts with a spring contact member 9 in the form of a curved segmental member whose base-portion is mounted at 9^a on an insulation 35 member 10 secured to the inner surface of the casing-cap A². At its outer side, the cap A², in the illustration given, is equipped with a terminal 11 with which connects a conductor 12 which may lead to the battery. The terminal 11 connects through a fuse 12^a with a clip 40 13 which is connected by a rivet 13^a with the base-portion of the spring-contact member 9.

The cap A² is shown equipped, also, with a terminal 14 which is in electrical contact with 45 the casing. If desired, a conductor (not shown) may extend from the terminal 14 to one terminal of the battery. Where the casing is in electrical contact with the frame of the automobile and thus grounded, it is unnecessary to employ a conductor in connection 50 with the clip 14.

One of the wires of the electric cable E is electrically connected at 15 with the main section of the reel B; and the other wire is 55 electrically connected at 16 with the annular contact member 7 of the reel.

Interposed between the annular contact member 7 of the reel and the spring-contact finger 9 carried by the removable cap of the 60 casing is a disk-like circuit-maker-and-breaker 17. In the illustration given, this comprises a radially disposed insulation strip journaled on a sleeve 18 which comprises a portion of the reel, this sleeve being in turn 65 journaled on the shaft B'. The insulation

member 17 may comprise a strip of material having smooth sides, such as a strip of formica or micarta. Preferably, a washer 19 is interposed between the member 17 and the adjacent insulation disk 8. The washer 19 preferably 70 is of insulation material without very smooth or polished surfaces. It is intended to serve as a friction member between the member 17 and the reel.

Interposed between the removable cap A² 75 of the casing and the circuit-maker-and-breaker 17 is a tension washer 20 which is provided with curved segmental arms 20^a which bear against the inner surface of the cap A². The latter is secured to the end of the shaft B' by means of a screw 21. As appears from Fig. 11, the edge of the circumferential wall of the main casing section A' is provided with a recess 22; and (see Fig. 10) the flange 23 of the cap section A² is provided with an inwardly struck lug 23^a which is adapted to register with and engage the recess 22.

In assembling the parts, the circuit-maker-and-breaker 17 is disposed in the position shown in Fig. 3; and when the cap A² is applied, with the lug 23^a engaging the recess 22, the spring-contact finger 9 will have its free end portion bearing on the member 17, as indicated by dotted lines in Fig. 3.

Assuming the spring C to be under suitable tension, the reel will operate to rewind the electric cord after the cigar-lighter has been in use. When the cigar-lighter is withdrawn from its socket, the cord E turns the reel against the force of its spring C. During the initial portion of the unwinding operation, the reel, through friction, turns the circuit-maker-and-breaker 17 in the direction indicated by the arrow in Fig. 3. This action continues until the advance edge of the member 17 strikes a stud, or stop, 24, which projects inwardly from the casing cap A². This arrests the movement of the member 17, but the movement of the reel continues as the cord is withdrawn outwardly. Almost immediately after the member 17 starts to move during the initial portion of the unwinding of the cord, said member 17 is withdrawn from the circuit-breaking position and permits the extremity of the spring finger 9 to fall into contact with the contact member 7 of the reel. This completes the electric circuit, it being understood that the current can pass outwardly through one wire of the cord E to the resistance wire of the cigar-lighter tip, thence from the resistance wire back through the other wire of the cord E to the main section of the reel, thence from the reel to the shaft B' and to the casing A.

The casing A is suitably grounded, or connected, with one side of the battery, and the spring-contact finger 9 is connected by means of the conductor 12 with the other side of the battery.

After the cigar-lighter has been used, the electric cord will be automatically wound upon the reel, assuming that the user releases his hold upon the cigar-lighter tip. During the initial portion of the rewinding operation, the reel acts frictionally to return the contact-maker-and-breaker 17 to the circuit-breaking position illustrated in Fig. 3, thus lifting the spring finger away from the annular contact-member 7 of the reel. The stop 24 operates again to arrest the movement of the member 17, while the reel is free to continue the operation of winding up the electric cord. It will be noted that inasmuch as the spring finger 9 is stationary (it does not rotate), and the circuit-maker-and-breaker 17 becomes stationary when arrested by the stop 24, the circuit will be interrupted very quickly after the rewinding movement begins and will continue in interrupted condition during the whole of the remainder of the rewinding operation.

From the description given, it will be understood that the circuit-maker-and-breaker 17 is capable of a limited oscillating movement through an arc of something less than 360° . The member 17 travels with the reel during the initial portion of the unwinding operation and during the initial portion of the rewinding operation, but the reel is capable of continuing its movement indefinitely (within the limit permitted by the cord), while the circuit is either completed or interrupted, depending upon the direction of movement of the reel.

In practice, it has been ascertained that the improved device will operate with certainty throughout a period far beyond that requisite for a cigar-lighter. In other words, the circuit-maker-and-breaker will remain practically operative throughout any possible life of the cigar-lighter as a whole. The improved circuit-maker-and-breaker is believed to be wholly novel, and it is desired to claim the same broadly.

In practice, the cigar-lighter tip D ordinarily is removably mounted in the tubular member D', which serves as a handle when the cigar-lighter tip is being used. As is well known, the shank of the cigar-lighter tip and the socket of the handle portion are provided with co-acting contacts through which the circuit to the resistance wire (not shown) is completed. Also, as is well understood in this art, the cigar-lighter tip may be removed and replaced by a lamp-bulb, if desired.

The foregoing detailed description is given for clearness of understanding only, and no unnecessary limitations should be understood therefrom, but the appended claims should be construed as broadly as permissible in view of the prior art.

What I regard as new, and desire to secure by Letters Patent, is:

1. In means of the character set forth, the combination of a frame, a spring-actuated reel mounted therein and equipped at one end with an annular contact-member, an electric cord connected with said contact-member and adapted to be wound upon said reel, a contact-member mounted on said frame and co-acting with said first-named contact-member, and an independently movable contact-maker-and-breaker interposed between said contact-members and journaled co-axially with said reel and actuated through a limited arc by the reel and permitting the reel to continue its rotation while the contact-maker-and-breaker remains at rest. 70 75 80

2. In means of the character set forth, the combination of a frame, a spring-actuated reel mounted therein and equipped at one end with an insulated annular contact-member, an electric cord connected with said contact-member and adapted to be wound upon said reel, a spring contact-member mounted on said frame and co-acting with said first-named contact-member, and an independently movable contact-maker-and-breaker of insulating material interposed between the planes of said contact-members and journaled co-axially with said reel and actuated through a limited arc by the reel and permitting the reel to continue its rotation while the contact-maker-and-breaker remains at rest. 90 95

3. In means of the character set forth, the combination of a frame, a spring-actuated reel mounted therein and equipped at one end with an insulated annular contact-member, an electric cord connected with said contact-member and adapted to be wound upon said reel, a spring contact-member mounted on said frame and co-acting with said first-named contact-member, and an insulation member interposed between said contact-members and journaled on the axis of said reel and frictionally actuated through a limited arc by said reel during the initial portions of the unwinding and the winding operations. 100 105 110

4. In means of the character set forth, the combination of a casing, a fixed shaft mounted in said casing, a reel journaled on said shaft, said reel having at one end an insulated annular contact-member, a spring having one end connected with said reel and the other end connected with said shaft, a spring contact-finger within said casing and mounted on one end thereof, a disk-like contact-maker-and-breaker interposed between said contact finger and the adjacent end of said reel and journaled co-axially with the reel, 115 said reel having frictional engagement with said contact-maker-and-breaker, means for limiting the rotative movement of said contact-maker-and-breaker, and an electric cord adapted to be wound on said reel and having 120 125 130

a conductor connected with said annular contact-member.

5. In means of the character set forth, the combination of a casing, a spring-actuated reel journalled therein, said reel having at one end a contact disk, a spring contact-member within the casing and mounted on one end thereof and co-acting with said contact disk, a disk-like contact-maker-and-breaker of insulating material interposed between said finger and disk and journalled concentric with the axis of said reel, and a friction disk interposed between said contact-maker-and-breaker and the adjacent end of said reel.

15. 6. In means of the character set forth, the combination of a reel provided with a contact disk, a co-acting spring contact-finger, and a frictionally actuated disk-like contact-maker-and-breaker interposed between said finger and reel and co-axially with respect to said reel.

7. In means of the character set forth, the combination of a reel provided with a contact disk, a co-acting spring contact-finger, and a disk-like frictionally actuated contact-maker-and-breaker of insulation material interposed between said finger and reel and journalled on the axis of said reel.

30. 8. In means of the character set forth, the combination of a reel provided with a contact disk, a co-acting spring contact-finger, a frictionally actuated disk-like contact-maker-and-breaker interposed between said finger and reel and journalled co-axially with respect to said reel, and a spring device serving to press said contact-maker-and-breaker towards said reel.

9. In means of the character set forth, the combination of a frame, a shaft fixedly mounted therein, a reel journalled on said shaft and having at one end an insulated annular contact-member, a spring connecting said reel and shaft, an electric cord adapted 40 to be wound on said reel and having a conductor connected with said annular contact-member and a conductor in electric connection with said shaft, a spring contact-member mounted in said frame and co-acting 45 with said annular contact-member, and a disk-like contact-maker-and-breaker of insulating material interposed between said contact-members and journalled to rotate concentrically with respect to said shaft and 50 frictionally actuated by said reel, and a stop carried by said frame adapted to limit the rotation of said contact-maker-and-breaker.

55. 10. In means of the character set forth, the combination of a reel equipped at one end 60 with a contact-member, a stationary shaft upon which said reel is journalled, a stationary spring contact-member co-acting with said first-named contact-member, means for imparting rotation to said reel, a frictionally 65 actuated circuit-maker-and-breaker inter-

posed between said contact-members and adapted to oscillate about the axis of said reel as a center, and a spring washer concentric with said shaft and serving to press said contact-maker-and-breaker towards said reel.

70. 11. In means of the character set forth, the combination of a metal casing, a shaft fixed therein, a metal reel journalled on said shaft and provided at one end with an insulated contact-disk, a spring connecting said shaft and reel, an electric cord adapted to be wound on said reel and having a conductor connected with said reel and another conductor connected with said contact disk, a spring contact-member insulatingly mounted on one end 75 of the casing and co-acting with said contact-disk, and a disk-like contact-maker-and-breaker of insulating material interposed between said contact-finger and said contact-disk and rotatable about said shaft as an axis, said contact-maker-and-breaker being frictionally actuated by said reel, and means for limiting the reciprocating movements of said contact-maker-and-breaker while the reel is permitted to continue its rotation.
